UNITED STATES PATENT OFFICE.

DOMENICO CELENZA AND MAX ROSEN, OF NEW YORK, N. Y.

UMBRELLA.

No. 857,157.

Specification of Letters Patent.

Patented June 18, 1907.

Application filed August 18, 1906. Serial No. 331,111.

To all whom it may concern:

Be it known that we, DOMENICO CELENZA and MAX ROSEN, subjects, respectively, of the King of Italy and the Czar of Russia, residing at New York, in the county of New York and State of New York, have invented certain new and useful Improvements in Umbrellas, of which the following is a specification, such as will enable those skilled in the art to which it appertains to make and use the same.

This invention relates to umbrellas, and the object thereof is to provide a device of this class which may be compactly folded together so that it can be carried in a grip-sack, dress-suit case or trunk; a further object being to provide an umbrella the stick or stick portion of which is composed of telescopic parts and the ribs of separate parts hinged together whereby the separate parts of the stick or stick portion of the umbrella may be telescoped, the ribs folded, the cover being also folded in this operation, and the entire device reduced to small dimensions; and with these and other objects in view the invention consists in an umbrella constructed as hereinafter described and claimed.

The invention is fully disclosed in the following specification, of which the accompanying drawing forms a part, in which the separate parts of our improvement are designated by suitable reference characters in each of the views, and in which;—

Figure 1 is a sectional side view of an umbrella made according to our invention, the separate parts of which are extended for use; Fig. 2 a view similar to Fig. 1 but showing the rib portions of the umbrella folded adjacent to the stick; Fig. 3 a detail view of the rib construction; and, Fig. 4 a view similar to Fig. 2 but showing the separate parts of the umbrella including the stick and ribs folded together so as to reduce the dimensions in order that the umbrella may be carried in a hand-bag, trunk or other receptacle.

The stick of our improved umbrella comprises, in the form of construction shown, four telescopic members *a*, *b*, *c* and *d*, of which the part *a* constitutes the handle proper, the part *b* the main part of the stick on which the runner-sleeve *e* is mounted, while the part *d* constitutes the tip end of the stick with which the rib-collar *f* is connected, the part *e* being intended primarily to strengthen the stick of the umbrella at the point where the greatest strain is thrown thereon.

The part *a* is provided with a spring pawl hole *a*², the part *b* is provided with four spring pawl holes *b*², *b*³, *b*⁴ and *b*⁵, and the part *d* is provided with two spring pawl holes *d*² and *d*³, while the part *c* is provided with two spring pawl holes *c*² and *c*³, and the runner-sleeve *e* with a spring pawl hole *e*². The part *a* is provided with a spring pawl *a*³, the runner-sleeve *e* with a spring pawl *e*³ and the part *d* of the stick with a spring pawl *d*⁴, and these pawls operate when the separate parts of the stick are extended as shown in Fig. 1, and when the separate parts of the stick are telescoped said pawls operate as shown in Fig. 4.

The ribs *g* are composed of two parts *g*² and *g*³ and the parts *g*² of said ribs are connected with the collar *f* in the usual manner, while the parts *g*³ of said ribs are connected with the parts *g*² as shown in Figs. 1 and 3. In making this connection the part *g*³ is fitted into the corresponding end of the part *g*² and said parts are connected by a pivot pin *h* which also forms a connection for the corresponding braces *i*. Each of the ribs *g*, or the part *g*³ thereof, is provided with a cord *j* which is connected therewith at *j*² and with the runner-sleeve *e* as shown at *j*³, and the object of this cord *j* is to hold the parts *g*³ of the ribs in position for use as shown at the left of Fig. 1.

It will be understood that the cover of the umbrella, which is not shown, is secured in place on the ribs *g* in the usual manner, said cover being connected, in practice, with the parts *g*³ of the ribs *g* at *k* and *k*², and when the stick portion of the umbrella, or the separate parts thereof, are telescoped as shown in Fig. 4 the parts *g*³ of the ribs *g* are folded at *h*, and in this operation the cover is also folded and the entire device may thus be made to assume the compact form shown in Fig. 4.

The pawl *d*⁴ of the part *d* of the stick only operates when the parts of the umbrella are in the position shown in Fig. 2, and the operation of the pawls *a*³ and *e*³ at this time is also shown in said figure, and when the parts of the umbrella are in the position shown in Fig. 4 this figure the umbrella may be used as a walking stick.

It will be understood that the cords or other flexible devices *j* which are connected with the outer or hinge portion *g*³ of the ribs *g* are intended to hold said parts of said ribs in position for use without interfering with

the folding thereof as shown in Fig. 4, and while I have shown the flexible supports *j* connected with the lower end portion of the runner-sleeve *e*, it will be apparent that said supports may be connected with other parts of the umbrella.

Having fully described our invention, what we claim as new and desire to secure by Letters Patent, is;—

10. 1. An umbrella the stick portion of which including the handle is composed of separate telescopic sections with one of which the ribs are connected in the usual manner, said telescopic sections being provided with spring 15 pawls which are adapted to hold them both in the telescoped and in the extended position, one of said telescopic sections of the stick and handle portion being provided with a runner-sleeve with which the braces are 20 connected, said runner-sleeve being provided with a spring pawl which operates to hold it on one of said telescopic sections in two different positions, the ribs of the umbrella being composed of separate parts hinged together 25 at the point where the braces are connected, and the adjacent ends of the separate parts of the ribs being overlapped, and the

outer end portions of the ribs being provided with flexible supports which are connected therewith and with the runner-sleeve.

2. An umbrella the stick portion of which including the handle is composed of four telescopic sections with one of which the ribs are connected in the usual manner, spring 30 pawls for holding said sections both in the telescoped and in the extended position, one of said telescopic sections being provided with a runner-sleeve with which the braces are connected, the ribs of the umbrella being composed of separate parts hinged together 35 at the point where the braces are connected therewith, and the outer end portions of the ribs being provided with flexible supports which are connected therewith and with the runner-sleeve.

In testimony that we claim the foregoing as our invention we have signed our names in presence of the subscribing witnesses this 16th day of August 1906.

DOMENICO CELENZA.
MAX ROSEN.
